[57] CLAIM

The ornamental design for a telecommunications connector panel, as shown and described.

DESCRIPTION

FIG. 1 shows a front elevation view of a first embodiment of my new design with the rear elevation view being a mirror image thereof;

FIG. 2 shows a bottom plan view thereof;

FIG. 3 shows a right end elevation view thereof with the left end view being a mirror image thereof;

FIG. 4 shows a cross-sectional elevation view thereof along the line 4—4 of FIG. 2;

FIG. 5 shows a top plan view thereof;

FIG. 6 is a front elevation view of a second embodiment of my new design with the rear elevation view being a mirror image thereof;

FIG. 7 shows a bottom plan view thereof;

FIG. 8 shows a right end elevation view thereof with the left end view being a mirror image thereof;

FIG. 9 shows a cross-sectional elevation view thereof along the line 9—9 of FIG. 7; and,

FIG. 10 shows a top plan view thereof.
